Primary Examiner — Bao-Yen T Nguyen*Assistant Examiner* — Christopher John Suarez La Rosa(74) *Attorney, Agent, or Firm* — Zagorin Cave LLP;
Robert W. Holland(57) **CLAIM**

The ornamental design for a briefcase as shown and described.

DESCRIPTION

FIG. 1 is a front perspective view of the briefcase comprising the present invention;

FIG. 2 is a front elevation view thereof;

FIG. 3 is a rear elevation view thereof;

FIG. 4 is a right side view thereof;

FIG. 5 is a left side view thereof;

FIG. 6 is a top view thereof; and,

FIG. 7 is a bottom view thereof.

Broken lines shown in the drawings illustrate stitching presented as part of the claimed design.
